UNITED STATES PATENT OFFICE

ROY E. HALL, OF LYONS, NEBRASKA

SAFETY SWINGING POST FOR MAIL BOXES

Application filed August 4, 1930. Serial No. 472,845.

This invention relates to certain new and useful improvements in supports found particularly applicable for rural free delivery mail boxes and the like.

- 5 One of the principal objects of the invention consists of a support of this character designed to normally dispose the mail box over and outwardly beyond the usual drainage ditch at the roadside.
- 10 Another object of the invention contemplates the provision and arrangement of means for yieldingly maintaining the box in the position stated.

An additional object of the invention embodies a means of adjustment for the box by means of which the latter may be adjusted to positions found suitable to the postman and recipient.

With the above and other objects in view, 20 the invention further consists of the following novel features and details of construction, to be hereinafter more fully described, illustrated in the accompanying drawings and pointed out in the appended claim.

25 In the drawings:—

Figure 1 is a side elevation of the present invention.

Figure 2 is a horizontal sectional view taken on line 2—2 of Figure 1.

30 Figure 3 is an enlarged detail sectional view taken through one of the several journals upon the support.

Figure 4 is a horizontal sectional view taken on line 4—4 of Figure 1.

35 Figure 5 is a sectional view taken on line 5—5 of Figure 4.

Referring to the drawings in detail where- 40 in like characters of reference denote corre- sponding parts, the reference character 10

indicates generally a standard or support, preferably of tubular formation and suitably anchored within the ground by concrete or the like. A cap member 11 for the uppermost open end of the tubular support 10, is 45 provided with a reduced extension 12 telescopedically positioned and journally associated within the uppermost end of the tubular support, in the manner best illustrated in Figure 3 of the drawings. A sleeve member 13,

50 telescopedically associated for rocking motion

with relation to the support, is cooperatively associated with the cap 11 and extension 12 therefor for simultaneous lateral shifting motion through the employment of a connecting rod 14. The end of the connecting 55 rod, fastened through the cap 11 outwardly and beyond the tubular extension 12, has formed thereon an eye 15, swivelly associated with the eye 16, formed upon the adjacent end of an adjusting rod 17; the purpose of 60 the latter mentioned rod will be better understood in the following description of the invention.

A supporting arm 18, provided with a clevis 19 upon its innermost end is designed 65 to accommodate the trunnions 20 outwardly projecting from diametrically opposite sides of the sleeve 13 in the manner shown in Figure 2 of the drawings and from which position the supporting rod may be raised and 70 lowered. An adjusting sleeve 21, slidably mounted upon the supporting arm 18, is provided with a set screw 22 designed for biting engagement with the supporting arm 18 to sustain the latter at any desired height. The 75 remaining end of the adjusting rod 17 is shaped to provide an eye 23 passed through an apertured ear 24 upon the adjusting sleeve 21.

The mail box or other receptacle, such as 80 indicated at 25, is mounted upon the upper side of a rod member 26, extensively associated with the outermost projecting end of the supporting arm 18 by means of which the mail box or receptacle 25 may project 85 outwardly over the highway, beyond the drainage ditch, for distances found most convenient to the postman and recipient.

A cross pin 28, carried by the standard 10, 90 has one end outwardly projected therefrom for disposition within a groove 29, horizontally disposed within the body of the sleeve 13 and wholly obscured from view. Compression springs 30, arranged within the groove 29 and sprung at their ends against the end walls of the channel and the opposed sides of the projecting extremity of the cross pin 28, serve to normally and yieldingly position the mail box in position, shown in Figure 1 of the drawings. A stop collar 31, 100

adjustably positioned upon the standard 10, is designed for abutting engagement with the lower periphery of the sleeve 13 to provide a support for the latter by means of 5 which the bearing strain may be equalized upon both the cap 11 and sleeve 13.

From the foregoing, it is understood that the mail box may be shifted laterally and at right angles to the position shown in Figure 10 1 of the drawings and in either direction to permit the recipient to remove the mail from the box or to permit the passing of a ditch digger, road scraper, hay wagon and the like without incurring any injury to the mail box 15 or the support structure therefor or in any way offering an obstruction to traffic.

The invention is susceptible of various changes in its form, proportions and minor 20 details of construction and the right is here- 25 reserved to make such changes as properly fall within the scope of the appended claim.

Having described the invention, what is claimed is:

25 A mail box support comprising a tubular standard, a cap mounted for turning movement in the upper end of the standard, a sleeve mounted for turning movement upon the standard at a point spaced below the cap, a rod connected at its opposite ends with the 30 cap and the sleeve respectively and having an intermediate portion in spaced parallel relation to the standard, a box supporting arm connected with the sleeve, a brace connecting said arm with the upper end of said rod and springs located interiorly of the 35 sleeve and engaging a stop member upon the standard to hold the arm at a normal position.

40 In testimony whereof I affix my signature.
ROY E. HALL.
